Inventor:
Heinrich Müller

UNITED STATES PATENT OFFICE

HEINRICH MÜLLER, OF NUEREMBERG, GERMANY

TOY

Application filed July 16, 1928, Serial No. 292,946, and in Germany April 4, 1928.

This invention relates to toys and more especially consists in further improvements provided on toys representing the figure of an animal or the like which is operated by 5 a mechanism in a manner to imitate natural motion, such as for instance the alternate downward and upward motion of a bird, when picking up food from the ground or a walking, dancing or similar motion of an 10 animal. The general features of the toy to which my present invention relates are described and claimed in a co-pending United States application for patent Serial No. 264,847, filed March 26, 1928, now U. S. 15 Patent No. 1,738,604, dated December 10, 1929.

My present invention consists particularly of a new construction relating to the manner of supporting the fly-wheel which is 20 mounted eccentrically within the body of a bird and serves for imparting the proper motion to the figure, and in connection therewith of a novel construction relating to the legs and feet of the bird which latter 25 construction is designed to especially facilitate the several steps of motion which shall be imparted to the body of the bird by action of said fly-wheel.

In the accompanying drawing which 30 forms part of this specification I have shown as an example of the construction according to my present invention a toy in the form of a bird provided with a new arrangement of the fly-wheel and the legs and feet according to my present invention. In the 35 drawing, Fig. 1 is a side-view of the toy partly broken away showing the interior driving mechanism thereof, Fig. 2 a front view and section to Fig. 1, Fig. 3 a bottom view taken on Fig. 1 and Figs. 4 to 7 are detail views, partly in section, showing the construction of the supporting feet according to my present invention. Fig. 8 shows in an enlarged scale the spring-driven mechanism of my present toy together with the 40 protective wall provided on said mechanism, Fig. 9 is an enlarged cross section through the body of the bird showing with particular clearness the way in which a cover of 45 texture or the like may be fastened to the

body of the toy as well as the action of said protecting wall in connection with the fastening of said cover.

Referring now more particularly to the drawing, the body 1 of the toy is made in 55 the form of a bird and may be provided with a cover of a texture or plush 1'. Within the body of the bird which may preferably be made from sheet-metal there is mounted a spring-operated driving mechanism 4, comprising an eccentrically mounted fly-wheel 6 as more fully described in my above-mentioned co-pending application Serial No. 264,847. The driving mechanism is mounted within the body of the toy in such a position 60 relatively thereto that said fly-wheel 6 will be positioned at a point about within the breast of the bird body, that is to say about midway between the beak and the foot plates or toes 20. In this manner the distribution 65 of the masses in the front and rear of said fly-wheel 6 will be such that the figure during rest of said fly-wheel will automatically be set back upon its feet. In addition to this on account of the position of the fly-wheel relatively to the body of the bird 70 there will be produced during rotation of said fly-wheel a displacement of the equilibrium 75 which displacement results into a tilting or oscillating motion, thus imparting to the body 80 of the bird a motion which imitates the natural picking motion. In addition to this picking motion the eccentric rotation of the fly-wheel which preferably is positioned outside of the plane of symmetry of the body of 85 the bird will impart to the toy also the natural hopping or dancing motion of the bird. The legs 13 are mounted on the bird body 1 and are extending so far to the front that the center of gravity of said body will be 90 positioned just above the points of support. In consequence thereof a very small displacement of the center of gravity will be necessary in order to impart a tilting or 95 similar motion of the bird body towards the front without any shocks or other irregularities. The motion imparted to the toy by action of the fly-wheel will be further favorably acted upon by the form of the foot plates 20 comprising toes of which the front 100

portion is somewhat upwardly bent so that the feet or supporting plates as a whole will be of the form of more or less arched supporting surfaces on which the body of the bird may be easily rocked or tilted towards the front and the rear in accordance with the periods of motion of the fly-wheel. A picking motion may thus also be produced during the hopping, dancing or similar motion of the toy. When producing said picking motion the body of the bird will alternately be supported by the point of the beak and the rear portion or toes of the foot plates 20. The foot plates 20 are fastened on the legs 13, said legs being flattened at their under somewhat downwardly bent ends as shown at 21 in Fig. 6, while the foot plates are provided with a slot or aperture 23 adapted to receive the flattened part 21 of the legs 13. At the place of the slot or aperture 23 the foot plate is somewhat upwardly bent as shown at 22. The flattened portions 23 of the legs 13 are inserted into said slots or apertures 23 and firmly fastened therein by riveting. The head of the rivet as indicated at 21' is positioned within the mould-shaped portion 22 of the foot-plate and countersunk therein in order to not interfere with the rocking motion of the body 30 of the toy on the arched supporting surfaces 20.

It is of course also possible to place the legs of the toy figure at such a position relatively to the body of the bird that the head parts thereof will have a slight over-weight so that the figure as shown in dotted lines in Fig. 1 in inoperative condition of the driving mechanism will be supported by the beak and the two supporting plates or legs of the bird. By action of the fly-wheel, however, the head portion of the body of the bird will be moved or rocked towards above, thus bringing about a motion imitating the natural picking motion of a bird.

In order to provide a simple cover of cloth, texture or the like on the body of the toy to imitate the natural plumage of a bird, the bird body is formed out of a metal sheet and provided with a joint as indicated at 18. The joint 18 may be firmly kept together by means of rivets or similar devices. The spring-actuated driving mechanism 4 is provided as particularly shown in Figs. 8 and 9 with a protecting wall 19 forming an extension of one of the plates of the driving work. The protecting wall 19 is so bent that it will overlap the joint 18 along the under side of the body of the toy.

The cover 1" imitating the plumage may now be easily placed over the body of the bird and its ends inserted into the joint 18 and firmly kept in position by the latter. At the same time the protecting wall 19 will have the effect, that the ends of the cover 1" which project through the joint 18 into

the interior of the body 1 will be positively kept out of the path of motion of said fly-wheel 6. The protective wall 19 in addition to this will also engage the joint 18 from within and provide a considerable reinforcement for said joint. This novel protecting wall according to my present invention will essentially simplify the mode of fastening ornamental covers or the like upon the body of the toy and at the same time safely prevent against any obstruction within the path of motion of the fly-wheel.

In order to provide during motion of the toy figure a counter-action against the tendency of the tilting of the toy towards the side opposite to the fly-wheel 6, the body 1 of the toy is provided with a surplus of mass on the side of the fly-wheel. This surplus of mass will now effectively counter-act the lifting motion exerted upon the toy by the fly-wheel and safely prevent the toy from falling towards the side opposite to the fly-wheel.

This one-sided surplus of mass given to the body of the toy may be accomplished in two ways, viz: either by providing a weight within the body of the toy or by properly shaping or positioning the legs. In the latter case no surplus of matter needs to be provided in order to produce a surplus of weight on one side of the toy.

This mode of providing a one-sided surplus of weight without the employment of any additional matter is shown in Fig. 2.

For this purpose the one leg 13 of the body of the toy which is positioned on the side of the fly-wheel 6 is made of somewhat smaller length than the other leg so that the toy will rest with a greater part of its mass upon said shorter leg, this causing the toy during operation of the fly-wheel to have a tendency of moving more easily towards said shorter leg.

Essentially the same effect may be attained by fixing the leg which is positioned on the side of the fly-wheel 6 to the body 1 of the toy at a smaller distance from the central plane of symmetry of the latter. The different distances of the legs from said central plane of symmetry are indicated in Fig. 2 at x and y . In this case the leg which is at a smaller distance from the plane of symmetry of the toy body may likewise be made of smaller length than the other leg.

I claim:

1. In a toy of the form of a bird, the combination of a frame mounted within the body of the bird, a spring-actuated driving mechanism mounted within said frame, an eccentrically mounted fly-wheel driven by said mechanism, and a protective wall associated with said frame to form a shield for the path of motion of said fly-wheel.

2. A toy of the form of a bird, comprising a body of sheet-metal having a joint along

its under side, a cover imitating the plumage of a bird and laid around said body of sheet-metal, the ends of said cover extending into said joint and being fixed therein, a driving mechanism provided within said body of sheet-metal, an eccentrically mounted fly-wheel driven by said driving mechanism, and a protective shield intermediate the path of motion of said fly-wheel and said ends of said cover when fixed in said joint, to prevent said ends of said cover from entangling with said fly-wheel when rotating.

3. A toy of the form of a bird, comprising a body of sheet-metal having a joint along its under side, a cover imitating the plumage of a bird and laid around said body of sheet-metal, the ends of said cover extending into said joint and being fixed therein, a driving mechanism provided within said body of sheet-metal, an eccentrically mounted fly-wheel driven by said driving mechanism, and a protective shield intermediate the path of motion of said fly-wheel and said ends of said cover when fixed in said joint, to prevent said ends of said cover from entangling with said fly-wheel when rotating, said protective shield engaging from within said edges of said sheet-metal to provide a re-inforcement for said body of sheet-metal.

30 4. A toy of the form of a bird comprising an eccentrically mounted fly-wheel positioned within the breast portion of the bird at a small distance from the center of gravity of the toy, driving means for rotating said fly-wheel, legs and supporting plates in the form of toes fixed on said legs, said supporting plates being bent upwardly at the front end thereof to provide an arched bottom surface on which the body of the bird may make 35 a rocking motion during rotation of the fly-wheel, said supporting plates being of sufficient length towards the rear to limit tilting of the toy in rearward direction.

In testimony whereof I affix my signature.
